David L. Meisske, of St. Louis Mo,
Letters Patent No 1292, dated July 31, 1860,

The schedule referred to in these Letters Patent and making part of the same.

To all whom it may concern:

Be it known that I, David L. Meisske, of the City comty of St. Louis and State of Missouri, have produced a new and original design to be used as a trade mark upon certain medicines of my own make, and I do hereby declare that the following is a full clear and exact description of the same, reference being had to the annexed drawing, which illustrates my design, and the letters of reference marked thereon.

The design aforesaid consists of a picture, to be printed upon paper or other similar substance.

Des. 1292

The design is composed of the following figures arranged and disposed as shown, that is to say. In the foreground of the picture a Female figure A, is seen standing in what appears to be low or marshy ground.

The said figure represents a woman gathering flowers, in her left hand she has a bunch gathered, and with her right hand she is gathering more.

And all over the surface of the ground upon which the aforesaid figures are represented: luxuriant herbage is represented, and in connection with the design aforesaid, and making part of the same are the words "D. L. Meineke, M.D.", written.

I claim as my production the above described picture or design to be used as a trade mark, upon any medicine or other article which I may manufacture.
